Primary Examiner — Cynthia Ramirez*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a top view of a shoe showing our design;

FIG. 2 is a front view thereof;

FIG. 3 is a first side view thereof;

FIG. 4 is a second side view thereof; and,

FIG. 5 is a front perspective view thereof.

The long and short broken lines form the boundary of the shoe and form no part of the claimed design. The even length broken lines of the remainder of the shoe are environment and form no part of the claimed design.
